(57) **CLAIM**

The ornamental design for a center cap bracket for a semitrailer wheel, as shown and described.

DESCRIPTION

FIG. 1 is a front perspective view of a center cap bracket for a semitrailer wheel, showing my new design;

FIG. 2 is a front elevation view thereof, the rear elevation view being a mirror image thereof;

FIG. 3 is a top plan view thereof;

FIG. 4 is a right-side elevation view thereof, the left-side elevation view being a mirror image thereof;

FIG. 5 is a bottom plan view thereof; and,

FIG. 6 is a section view taken of FIG. 3 along line 6-6.

The evenly spaced broken lines shown in the drawings depict portions of the center cap bracket for a semitrailer wheel that form no part of the claimed design.
